(57) **CLAIM**

The ornamental design for a battery housing for electric work vehicle, as shown and described.

DESCRIPTION

FIG. 1 is a front, top, and left perspective view of a battery housing included in an electric work vehicle;

FIG. 2 is a front, top, and left perspective view of a battery housing for an electric work vehicle;

FIG. 3 is a rear, bottom, and left perspective view of a battery housing for an electric work vehicle;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The dash-dash broken lines in the drawing views are included to show portions of the battery housing for electric work vehicle that form no part of the claimed design. The dash-dot broken lines in the drawing views are included to show claim boundaries that form no part of the claimed design.

1 Claim, 9 Drawing Sheets
